UNITED STATES PATENT OFFICE.

ARTHUR M. EBBETS, OF SAN FRANCISCO, CALIFORNIA.

DESIGN FOR A BADGE.

SPECIFICATION forming part of Design No. 18,730, dated November 13, 1888.

Application filed August 7, 1888. Serial No. 282,181. Term of patent 14 years.

To all whom it may concern:

Be it known that I, ARTHUR M. EBBETS, a citizen of the United States, residing at the city and county of San Francisco, State of California, have invented and produced a new and original Design for Badges, of which the following is a specification, reference being had to the accompanying drawing, forming part hereof.

(c) The figure is an elevation of a badge showing my design.

The leading feature of my design is the center-piece, in the form of a grizzly bear, encircled by a rim-piece in the form of a laurel wreath. 15 In connection therewith, other features are a star at the top of the rim-piece and a scroll-plate below the center-piece and crossing the rim-piece.

A is the center piece of the badge, in the form 20 of a grizzly bear.

B is the rim-piece of the badge, in the form and appearance of a wreath of laurel. This rim-piece encircles the center-piece, which is

arranged transversely, as shown. Across the rim-piece is a scroll-plate, C. The scroll-plate 25 may be of any suitable design, such as the extended ribbon or scroll here shown. Formed at the top of the rim-piece B is a star, D.

I am aware of the common use of the figure of a grizzly bear in many designs, and I do not 30 herein claim this alone as forming a novel feature in my design; but

What I do claim is—

The design for a badge herein shown and described, the same comprising the center-piece A, representing a grizzly bear, the rim-piece B, representing a laurel wreath encircling the center-piece, the scroll-plate C across the lower portion of the rim-piece, and the star D on the top of the rim-piece, as set forth. 40

In witness whereof I have hereunto set my hand.

ARTHUR M. EBBETS.
